Patented Jan. 14, 1919.

Inventor
William G. Flint

UNITED STATES PATENT OFFICE.

WILLIAM G. FLINT, OF LOS ANGELES, CALIFORNIA.

DESIGN FOR A STATUETTE OR SIMILAR ORNAMENT.

52,871.

Specification for Design.

Patented Jan. 14, 1919.

Application filed June 5, 1918. Serial No. 238,411. Term of patent 3½ years.

To all whom it may concern:

Be it known that I, WILLIAM G. FLINT, a citizen of the United States, residing at Los Angeles, in the county of Los Angeles and State of California, have invented a new, original, and ornamental Design for a Statuette or Similar Ornament, of which the following is a specification, reference being had to the accompanying drawing, forming part thereof.

The figure is a plan view of a statuette or similar ornament, showing my new design.

I claim—

The ornamental design for a statuette or similar ornament, as shown.

WILLIAM G. FLINT.
